ELECTRICAL SIGNAL TRANSMISSION
SYSTEM

Charles de Vriendt and Lucien A. B. Cabes, Antwerp, Belgium, assignors to International Standard Electric Corporation, New York, N. Y., a corporation of Delaware

Application April 1, 1943, Serial No. 481,511
In the Netherlands June 21, 1941

Section 1, Public Law 690, August 8, 1946
Patent expires June 21, 1961

12 Claims. (Cl. 179—16)

1

The invention relates to signal transmission systems and more particularly to pulse-receiving circuits.

Heretofore, in modulated carrier wave pulse-receiving circuits, it was the practice, either to impress the rectified modulated carrier wave, through an appropriate combination of filter and transformer, directly on a stepping relay, or to apply the carrier wave by means of a suitable transformer to the grid of a hot-cathode vacuum tube, in which the stepping relay was inserted in the plate circuit.

Both these methods have however certain disadvantages and the object of the present invention is generally to improve and simplify modulated carrier pulse-receiving circuits.

The invention will now be described with the aid of the accompanying drawings of which Fig. 1 shows a schematic circuit arrangement according to the present invention, while Fig. 2 shows a modification thereof.

In Fig. 1 IMP designates an impulse sender, which may be the dial of a telephone apparatus, or a mechanical impulse machine, or any other similar appliance. Relay Sr is the stepping relay at the sending end, which connects one of the different frequencies f_1 and f_2 to the signalling wire.

At the receiving end there are two filters, two cold-cathode tubes, two controlling relays and some auxiliary apparatus.

One filter, consisting of condenser C_1 and inductance S_1 , is tuned in such a way that resonance occurs with frequency f_1 .

The other filter consists of condenser C_2 and the primary winding of transformer T, which winding is shunted by condenser C_3 . The second filter is tuned in such a way, that resonance occurs with frequency f_2 .

The cold-cathode tubes referred to in this invention are of the well-known type, which requires a specific control gap breakdown potential V_x in order to ionize the control gap between the two electrodes e_1 and e_2 , whereas a substantially higher main gap breakdown potential V_y is required to ionize this main gap between the anode A and each of the two electrodes e_1 and e_2 .

Once the control gap has been ionized, however, a sustaining potential V_z , which may be considerably lower than V_y , is sufficient to maintain a current in the main gap.

It will be seen from Fig. 1 that the anode of

2

tube L_1 is connected in series with relay Ar_1 , while the anode of tube L_2 is connected in series with relay Ar_2 . The electrodes e_2 are connected to the negative sides of a potentiometer P, which is connected in parallel to a battery of 130 volts, while the electrodes e_1 (the control electrodes) are connected to a biasing potential on the potentiometer, which is smaller than the control gap breakdown voltage required to ionise the control gap.

5 The two controlling relays Ar_1 and Ar_2 control the two cold-cathode tubes in a manner as will be described below. Relay Ar_1 is the actual tube control relay, whereas relay Ar_2 is the signal reproducing relay.

10 The arrangement shown in Fig. 1 functions in the following manner.

When impulsing is about to start, the controlling circuit at the sending end connects a potential of frequency f_1 to the signalling wire via the back contact of relay Sr . This potential causes a circuit to flow through filter C_1-S_1 , which is tuned to the frequency f_1 , thereby increasing the potential on the control electrode e_1 of tube L_1 , to such an extent, that the control gap breakdown voltage is reached. The control gap is consequently ionised. At this moment the anode circuit of tube L_1 is still open at the right front contact of relay Ar_2 , so that nothing further happens.

15 As soon as the first impulse starts, in other words, as soon as the impulse sender IMP connects a ground to relay Sr for the first time, this relay operates and connects a potential of frequency f_2 (instead of f_1) to the signalling wire.

20 This potential causes a current to flow through the back contact of relay Sr and the filter C_2-T , which is tuned to the frequency f_2 , thereby inducing in the secondary winding of transformer T a potential, which is added to the biasing potential of electrode e_1 of tube L_2 , and which increases this potential to such an extent that the control gap breakdown voltage is reached. The control gap is consequently ionised, resulting in the immediate ionisation of the main gap and the operation of

25 relay Ar_2 in the anode circuit of the tube L_2 . When operated this relay closes the receiving end signal circuit via its left front contact and prepares the anode circuit of relay Ar_1 over its right front contact.

30 As soon as the first impulse starts, in other words, as soon as the impulse sender IMP connects a ground to relay Sr for the first time, this relay operates and connects a potential of frequency f_2 (instead of f_1) to the signalling wire.

35 This potential causes a current to flow through the second filter C_2-T , which is tuned to the frequency f_2 , thereby inducing in the secondary winding of transformer T a potential, which is added to the biasing potential of electrode e_1 of tube L_2 , and which increases this potential to such an extent that the control gap breakdown voltage is reached. The control gap is consequently ionised, resulting in the immediate ionisation of the main gap and the operation of

40 relay Ar_2 in the anode circuit of the tube L_2 . When operated this relay closes the receiving end signal circuit via its left front contact and prepares the anode circuit of relay Ar_1 over its right front contact.

45 To this may be added that at the moment the armature of relay Sr leaves its back contact, the potential of frequency f_1 is removed from the signalling wire with the result that the tube L_1 is extinguished; its anode circuit being already

50 open.

When the first impulse is over, i. e. when the impulse sender IMP removes the ground from relay S_r , this relay releases, thus removing the potential of frequency f_2 from the signalling wire. Tube L_2 remains, however, ionised, after the armature of relay S_r leaves its front contact, because its anode circuit remains closed. As soon as the armature of relay S_r closes its back contact, a potential of frequency f_1 is connected to the signalling wire. This potential causes the ionisation of the control gap of tube L_1 as explained above and at this moment also the main gap of tube L_1 becomes ionised, the anode circuit through relay A_{r1} being closed via right front contact of relay A_{r2} .

Relay A_{r1} therefore operates and as soon the armature leaves the back contact, the anode circuit of tube L_2 is opened, whereupon this tube extinguishes. As a consequence relay A_{r2} releases, opening the receiving end signal circuit and interrupting the anode circuit of tube L_1 , thus causing the release of relay A_{r1} .

The control gap of tube L_1 remains ionised due to the presence of a potential of frequency f_1 on the signalling wire, as explained above.

A non-inductive resistance r_4 is connected in parallel to the winding of relay A_{r1} for the purpose of discharging the relay as soon as its operating circuit is opened. This is desirable in order to speed up the de-ionisation of tube L_1 .

One impulse has now been transmitted and the circuits are in the same condition as at the moment the impulsive started.

All subsequent impulses are transmitted in exactly the same manner.

From the above description it follows that the invention as illustrated by Fig. 1 provides a very sensitive signal transmission, suitable for instance for application in local impulse transmitting circuits or similar circuits for transmission over long distances.

The invention is based on the principle that each pulse or signal comprises two components of different frequencies, which are separated at the receiving end by adequate filters, each of the two different components being utilised to ionize alternately a cold-cathode tube.

In Fig. 2 an alternative arrangement is shown, which differs from Fig. 1 in the manner in which the anode circuits of the tubes have been designed. In Fig. 2 the anode control relay has been replaced by a condenser C_4 , while the signal relay A_{r3} has been connected in series with both anodes.

The scheme functions as follows:

When impulsive is about to start, a frequency f_1 is connected to a signalling wire and, as previously explained, tube L_1 is ionised, an anode current now flowing through the resistance r_3 . Since the sustaining voltage of tube L_1 is about 75 volts, the potential at point "a" will be about -55 volts with respect to point "O." Condenser C_4 will consequently be charged in a direction indicated by + and - in full lines, since point "b" is of the same potential as point "O."

As soon as the impulsive starts, relay S_r operates and frequency f_2 is connected to the signalling wire, causing the ionisation of tube L_2 and the operation of the stepping relay A_{r3} . The potential at point "b" will now fall to -55 v. with respect to point "O," with the result that condenser C_4 will discharge. This discharge current will cause an additional, temporary voltage drop across resistance r_3 , which will produce a lowering of the potential of point "a" with respect to

point "O." Since the total voltage across the main gap circuit is 130 volts and since the voltage drop across resistance r_3 is greater than 55 volts, the available voltage between the main gap of the tube will be less than 75 volts (sustaining voltage) with the result that tube L_1 will extinguish.

At the moment the current through r_3 disappears, point "a" will attain the same potential as point "O." Condenser C_4 will now be charged in opposite direction, indicated by + and - in dotted lines.

When the first impulse is over, relay S_r releases and frequency f_1 is again connected to the signalling wire. The tube L_1 will then become ionised and the potential of point "a" will again drop to about -55 volts with respect to point "O." Condenser C_4 will now start to discharge and the discharge current causes an additional voltage drop in relay A_{r3} , which results in the extinction of tube L_2 and the release of relay A_{r3} .

Point "b" will then attain the same potential as point "O" and the original conditions will again be re-established.

Each impulse is reproduced in exactly the same way as described above.

What is claimed is:

1. An electrical signal transmission system comprising a transmission line, signal transmission apparatus connected to one terminal of said line, said signal transmission apparatus comprising means to transmit alternate impulses of two different frequencies, means connected to the opposite end of said line for receiving said impulses said receiving means comprising a pair of circuits, means in one circuit responsive to energy of one of said frequencies applied thereto to register the beginning of an impulse and means in the other of said circuits responsive to energy of the other of said frequencies applied thereto to register the end of an impulse and relay means associated with said receiving means jointly controlled by both of said circuits for retransmitting signals measured by the two frequencies of each impulse received.

2. An electrical signal transmission system according to claim 1 in which said signal transmitting device comprises a substation dial, a relay controlled thereby, contact means for said relay including a tongue, front and back contacts operating therewith, a source of a first signalling frequency potential connected to said back contact, a source of a different frequency potential connected to said front contact, said tongue being connected to said transmission line.

3. An electrical transmission system according to claim 1 in which said receiving means comprises electrical filter means for segregating the two currents of different frequencies.

4. An electrical transmission system according to claim 1 in which said receiving means comprises electrical filter means for segregating the two currents of different frequencies, a pair of cold cathode tubes, circuits connecting the control electrodes of the respective tubes to said filter means so that each tube is operated by a separate frequency.

5. An electrical transmission system according to claim 1 in which said receiving means comprises electrical filter means for segregating the two currents of different frequencies, a pair of cold cathode tubes, circuits connecting the control electrodes of the respective tubes to said filter

means so that each tube is operated by a separate frequency, a common source of biasing potential for each tube of such value that each signal component received will cause the operation of the corresponding tube.

6. An electrical transmission system according to claim 1 in which said receiving means comprises electrical filter means for segregating the two frequency components of the respective impulses a pair of cold cathode tubes, circuits connecting the control electrodes of the respective tubes to said filter means so that each tube is operated by a separate frequency of the received impulses, a pair of relays, of which one is connected in the anode circuit of each of said tubes whereby the relays operate on the operation of the corresponding tube, and circuits controlled from the contacts of the respective relays for controlling the extinguishing of said tubes.

7. An electrical signal transmission system comprising a transmission line, signal transmission apparatus connected to said line, said apparatus comprising means to transmit alternate impulses of two different frequencies, means connected to the opposite end of said line for receiving said impulses, said receiving means comprising electrical filter means, for segregating the frequencies of the respective impulses, a pair of cold cathode tubes, a circuit connecting the control electrode of each of said tubes to said filter means so that each tube responds to the application of energy of a different frequency of the respective impulses, a relay connected in the anode circuit of each tube, the relay associated with the first of said tubes being connected in an operating circuit including the back contact of the other relay, while the operating circuit of the latter relay includes the front contacts of the relay associated with the first of said tubes, the arrangement being such that the first of said tubes and the relay associated therewith operates an impulse of the first frequency and closes at its front contacts an operating circuit for the other relay which operates when the second of said tubes is operated by receipt of impulse the second frequency thereby at its back contact opening the circuit for the first of said tubes and the associated relay, the latter on releasing opening the operating circuit for the second tube and

the associated relay, and further contact means operated by the relay associated with the first of said tubes for transmitting impulses.

8. An electrical signal transmission system comprising a transmission line, signal transmission apparatus connected thereto, said apparatus comprising means to transmit alternate impulses of two different frequencies, one of said frequencies indicating the beginning of an impulse and the other the end thereof, receiving means connected to said line comprising electric filter means for segregating said respective frequencies, a pair of electronic tubes operatively connected to said filter means whereby one tube responds to application of energy of an impulse of one frequency and the other tube to application of energy of an impulse of the other frequency, relay means connected to the output circuit of said tubes so as to respond to the operation thereof, and means controlled by said relay means for retransmitting impulses.

9. A signal transmission system according to claim 8 in which said relay means is a single relay.

10. A signal transmission system according to claim 8 in which said relay means comprises a single neutral relay.

11. A signal transmission system according to claim 8 in which said relay means comprises a single neutral relay and in which condenser means connected across the output of said electronic tubes is used to control said relay means.

12. A signal transmission system according to claim 8 in which said relay means comprises a single neutral relay and in which a condenser is connected between the output electrodes of said electronic tubes, said condenser being used to control said relay means.
